(57) **CLAIM**

The ornamental design for a key storage lock box, as shown and described.

DESCRIPTION

FIG. 1 is a front right perspective view of a key storage lock box showing my new design.

FIG. 2 is a front elevational view of a first embodiment of the design with a front cover shown in a closed position.

FIG. 3 is a top plan view thereof. FIG. 4 is a right side elevational view thereof, the left side elevational view being a mirror image.

FIG. 5 is a rear elevational view thereof.

FIG. 6 is a bottom plan view thereof.

FIG. 7 is a front right perspective view thereof showing a cover of the design in an open position.

FIG. 8 is a front right perspective view of an alternate embodiment of the design without the front cover.

FIG. 9 is a front elevational view of the alternate embodiment; and,

FIG. 10 is a right side elevational view of the alternate embodiment, the left side view being a mirror image thereof, the top and bottom plan and rear elevational views being the same as shown with respect to the first embodiment.

The portions of the design shown in phantom lines form no part of the claimed invention.
